UNITED STATES PATENT OFFICE.

LESLIE COLBY WENTWORTH, OF WEBSTER, MASSACHUSETTS.

ADJUSTABLE CHAIR.

No. 882,983.

Specification of Letters Patent. Patented March 24, 1908.

Application filed May 8, 1907. Serial No. 372,553.

To all whom it may concern:

Be it known that I, LESLIE C. WENTWORTH, a citizen of the United States, residing at Webster, in the county of Worcester 5 and State of Massachusetts, have invented a new and useful Adjustable Chair, of which the following is a specification.

This invention relates to improvements in stands for supporting chairs, tables, and 10 other articles in different adjusted positions, and it has for its object more especially to provide a stand that is particularly adapted for use in connection with chairs such as those used in factories and other places where 15 it is desirable to adjust the chair vertically, angularly, and also in a direction toward and from the bench or table at which the operators are working, whereby the chairs may be adjusted exactly according to the wishes 20 or requirements of each individual, the chair support or stand occupying a minimum of floor space so that the waste may be easily removed and the floors cleaned without disturbing the occupant of the seat. 25 A further object of the invention is to provide a stand or support of the character described, that may be made and sold at a relatively small cost, is durable and not liable to get out of order, and that is capable of being 30 used generally on tables and various other articles wherein it is desirable or necessary to support the same in different adjusted positions.

To these and other ends, the invention 35 comprises the various novel features of construction and combination and arrangement of parts, which will be hereinafter more fully described and pointed out particularly in the claims appended hereto.

40 In the accompanying drawings:—Figure 1, is a side elevation of a chair constructed in accordance with the present invention. Fig. 2 represents a partial central vertical section on the line 2—2 of Fig. 1. Fig. 3 is a 45 detail view of an automatic locking device for supporting the chair in different vertical positions relatively to the base.

Corresponding parts in the several figures are indicated throughout by similar characters of reference.

As previously stated, the invention is capable of being applied to chairs, tables, and

various other articles wherein it is desirable to support them in different positions of adjustment, and, in the present embodiment 55 of my invention, it is shown in connection with a chair of a kind that is adapted for use in factories, stores, and other places wherein it is desirable to arrange the chairs in coöperative relation with a bench, counter, table, 60 or other object.

The chair shown in the present embodiment of the invention is especially adapted for use in factories, as it permits the operator to have his chair adjusted exactly according 65 to his wishes, either as to elevation, angular relation between the chair and the bench, or as to the distance between the chair and the bench, and it comprises, in the present instance, a base 1 having a flange 2 adapted 70 to rest upon the floor or other support, the flange being preferably perforated to receive screws or other devices for fastening the base in place. The base is provided with a centrally arranged upwardly extending stem 3, 75 and arranged transversely of the latter is a guide 4 which extends parallel to the attaching flange. The guide is provided with a longitudinally extending slot 5, and coöperating with the guide is a segmental bracket 6 having a vertically extending portion which engages one side of the guide at points above and below the slot, and being provided with a laterally offset bearing portion 7 which rests upon the top of the guide and serves 80 to sustain the weight imposed upon the bracket, the latter being capable of operating longitudinally of the guide. Suitable means are employed for locking the guide in different positions of adjustment in a direction longitudinally of the guide on the base, the device shown in the present instance embodying a screw or bolt 8 having its head arranged at one side of the guide, and its stem extending loosely through the slot of 85 the guide and into the bracket, the screw or bolt being preferably threaded into the bracket so that a turning movement of its head will serve to tighten or loosen it, although, if so preferred, a simple bolt connection 90 may be employed for clamping the guide and bracket in fixed relation.

The upper side of the bracket is preferably of segmental form and corrugated or notched,

as shown at 9 in Fig. 1, and coöperating with this segmental surface is a complementary bearing member 10 which is arranged on the lower end of a post 11, the said bearing member being provided, in the present instance, with a segmental slot 12, and an upper clamping surface 13 which is formed concentrically with the coöperating bearing surfaces of the bracket and bearing member.

10 The construction just described permits a relative tilting movement of the chair supporting post in a plane parallel to the plane of adjustment in a direction longitudinally of the guide, and the post is locked in the 15 different angular positions of adjustment relative to the base by means of a screw or bolt 14 which is threaded into the laterally offset portion 7 of the bracket and coöperates with the concentric clamping surface 20 13, tightening of the screw or bolt serving to draw the coöperating bearing surfaces of the post and guide closely together, the corrugations serving to positively prevent relative angular movement of the post relatively to the base.

The upper end of the post is provided with a laterally turned lug 15 having a bore 16 extending vertically therethrough and substantially in alignment with the axis of the 30 base when the post is in central position, and this lug serves to support the shaft 17, the upper end of the latter revolvably fitting a bearing 18 formed in a socket 19 which is rigidly secured to the under side of the chair 35 or other object to which the invention is applied.

Any suitable means may be employed for securing the shaft at different positions of adjustment in a direction vertically of the 40 post, the means shown in Figs. 1 and 2 comprising a set screw 20 threaded through one side of the lug and serving to clamp the shaft, rotary movement of the shaft being permitted by reason of the loose connection 45 between the socket thereon and the upper end of the shaft. In those cases where a set screw is employed for securing the shaft in different positions of adjustment in a direction vertically of the supporting post, the 50 elevation of the chair or other object relatively to the base may be adjusted by loosening the set screw.

In order to facilitate the vertical adjustment of the chair, an automatic locking device is provided which embodies, in the present instance, a collar 21 having a bore 22 which is substantially the size of the shaft at the upper end of the collar and is enlarged toward the lower end of the latter for the purpose of permitting a relative tilting between the collar and the shaft, which will produce a clamping action between the relatively sharp edges of the collar at the narrow portion of its bore and the shaft. The locking collar

is provided with a foot or lug 23 which is offset laterally of the axis of the collar and adapted to rest upon the top of the supporting post, the weight of the chair being sustained by the collar and the offset foot of the latter resting upon the top of the post produces a clamping action between the collar and the shaft that will prevent a vertical movement of the latter relative to the supporting post.

The invention is particularly applicable to 75 chairs or stools such as are employed in factories, stores, and similar places, as the chair may be adjusted in a direction toward and from the bench or counter by loosening the screw 8 and sliding the bracket in the 80 proper direction on the guide 4, and the angular relation between the chair and the bench may be varied by loosening the screw 14 and turning the supporting post relatively to the bracket, while the vertical position or 85 elevation of the chair may be adjusted after the set screw 20 of the locking collar 21, as the case may be, is released, and the chair is free to revolve on the upper end of the vertical shaft.

90 What is claimed is:—

1. In a stand of the character described, the combination with a suitable base, and a bracket supported thereon, of a supporting post having a laterally turned portion at its 95 lower end arranged to coöperate with the said bracket and having a laterally turned portion at its upper end provided with an aperture having its axis arranged substantially in alignment with the laterally turned 100 portion first mentioned, a shaft extending through the said aperture and adjustable vertically relatively to the post, and a device for locking the shaft and the post in fixed relation.

2. In a stand of the character described, the combination with a suitable base, and a bracket supported thereon, of a supporting post having a laterally turned portion at its lower end arranged to coöperate with the 110 said bracket and having a laterally turned portion at its upper end provided with an aperture having its axis arranged substantially in alignment with the laterally turned portion first named, a shaft extending through 115 the aperture and adjustable vertically relatively to the post, and means for automatically locking the shaft and post in fixed relation.

3. In a stand of the character described, 120 a base having a stem, a longitudinally slotted guide carried by the stem and disposed parallel with the base, a segmental toothed bracket having an offset bearing upon the guide, a clamping bolt passing through the slot and 125 into the bracket for holding the latter in adjusted positions relatively to the guide, a post having a toothed segmental longitudi-

nally slotted offset bearing upon the bracket and interlocking with the teeth thereof, a bolt passing through the slotted offset and into the bracket for holding the post in adjusted positions relatively to the bracket, and a vertically adjustable shaft carried by the post.

In testimony that I claim the foregoing as my own, I have hereto affixed my signature in the presence of two witnesses.

LESLIE COLBY WENTWORTH.
